UNITED STATES PATENT OFFICE.

WILLIAM EDWIN THRASH, OF ST. LOUIS, MISSOURI, ASSIGNOR TO
INTERNATIONAL CONSERVATORY OF MUSIC, OF DALLAS, TEXAS,
A CORPORATION OF TEXAS.

DESIGN FOR A MUSIC-INDICATOR.

No. 38,226.

Specification for Design.

Patented Sept. 4, 1906.

Application filed July 12, 1906. Serial No. 325,975. Term of patent 14 years.

To all whom it may concern:

Be it known that I, WILLIAM EDWIN THRASH, a citizen of the United States, residing at St. Louis, in the State of Missouri, have invented a new, original, and ornamental Design for Music-Indicators, of which the following is a specification.

In the accompanying drawing the figure is a view in elevation of a music-indicator, showing my new design.

I claim—

The ornamental design for a music-indicator, as shown.

WILLIAM EDWIN THRASH.
